UNITED STATES PATENT OFFICE.

WILLIAM C. DAY, OF RUMFORD FALLS, MAINE, ASSIGNOR TO THE NATIONAL DRAFTING TOOL COMPANY, OF LIVERMORE FALLS, MAINE.

COMBINED DRAFTING AND MEASURING TOOL.

SPECIFICATION forming part of Letters Patent No. 664,727, dated December 25, 1900.

Application filed March 22, 1900. Serial No. 9,676. (No model.)

To all whom it may concern:

Be it known that I, WILLIAM C. DAY, of Rumford Falls, in the county of Oxford and State of Maine, have invented certain new and useful Improvements in a Combined Drafting and Measuring Tool, of which the following is a specification.

This invention relates to dividers or compasses, calipers, and similar drafting or measuring tools in which the legs are connected by equalizing devices and in which means are provided for permitting either a quick adjustment of the legs or a fine and slow adjustment of the legs in tools of this character.

The invention consists in certain features of improvement in structure and arrangement, which I shall now proceed to describe and claim.

Of the accompanying drawings, forming a part of this specification, Figure 1 represents a side elevation of a tool constructed in accordance with my invention and arranged to be used as dividers. Fig. 2 represents a vertical sectional view. Fig. 3 represents a section on line 3 3, Fig. 1, on an enlarged scale. Fig. 4 represents in separate views the upper ends of the legs detached. Fig. 5 represents in separate views the pivot-block and adjusting device, detached. Fig. 6 represents a section on line 6 6 of Fig. 1.

The same reference characters indicate the same parts in all the figures.

In the drawings, *a a* are the legs of the instrument, each of which is preferably of angular form, as shown in Fig. 1. The lower portion of each leg I have represented by dotted lines as socketed and provided with a collar *a*³, having a set-screw *a*⁴, whereby extensions *i i* of different form may be secured to the legs and readily removed, the form of the extension depending upon the use to which it is desired to put the instrument. Either of the extensions *i* can be fastened in its respective socket by the pressure of the end of the set-screw *a*⁴ against the outside wall of the socket, pressing or bending the latter inward sufficient to obtain the necessary friction between the said extension and the inner surface of the socket. Obviously, however, the wall of the socket opposite the

inner end of the set-screw may be cut away; so that said set-screw may bear directly against the extension *i*. In the present case the extensions are pointed to serve as dividers-legs. One of these may be adapted to hold a pencil. The legs *a a* are formed at their upper ends with ears *a' a'*, which bear on opposite sides of a central pivot-block *b*, having trunnions *b' b'*, on which the ears are fitted to turn. The ears are held on the trunnions by screws *c c*, entering tapped orifices in the trunnions, and washers *c' c'*, held by the heads of the screws against the outer faces of the ears.

On the inner sides of the arms *a a* are formed recesses *a*⁵ *a*⁵, in which are pivoted on pins *e' e'* the upper ends of two links *e e* of equal length. The lower ends of said links are pivoted on pins *e' e'* between ears formed on a collar *f*. Said collar slides on the lower end of a rod *d*, depending centrally between the legs *a a* from the pivot-block *b*. A stud *f'* passes through the collar *f* and has an orifice *f*², Fig. 7, through which the rod *d* passes. Said stud is screw-threaded to engage a clamping-nut *f*³, which bears against one side of the collar. When the nut is tightened, the stud *f'* exerts lateral pressure against the rod *d*, holding it from sliding in the collar. The spreading apart of the legs *a a*, acting on the collar *f* through the links *e e*, moves said collar upward on the rod *d* in the direction of the pivot-block *b*, while the closing of the legs toward each other produces a reverse movement of the collar along the rod. By screwing the set-nut *f*³ tight against the collar *f*, and thereby clamping the collar *f* to the rod *d*, the legs *a a* are held immovable at the distance apart to which they have been moved, except when further adjusted by the longitudinal movement of the rod caused by the means which I shall now describe.

*b*² represents a tubular socket formed on the pivot-block *b* and projecting upwardly therefrom. In said socket is fitted to rotate an internally-tapped sleeve or adjusting-nut *b*³, which has a milled head *b*⁴, by which it may be rotated. The upper portion of the rod *d* is threaded to engage the internal thread of the sleeve or nut *b*³, the rod being fitted to slide in an orifice extending through

the pivot-block *b*. When the nut *b*³ is rotated, the rod *d* is raised or lowered, as the case may be, and a slow movement is imparted from it to the legs *a a* through the collar 5 *f* and links *e e*, the legs moving simultaneously in opposite directions. Endwise movement of the nut *b*³ is prevented by a segmental wire key or pin *b*⁵, which is inserted through a slot *b*⁶, Fig. 1, formed in one side 10 of the socket *b*², and enters coinciding grooves in the inner surface of the socket and the external surface of the adjusting-nut. A spring *j* is interposed between the bottom of the socket *b*² and the lower end of the adjusting- 15 nut, said spring exerting upward pressure on the nut and on the rod *d* and taking up any lost motion that may exist in consequence of looseness in the various joints and connections and preventing any looseness of the 20 legs *a a*.

It will be seen that the socket *b*², projecting above the pivot-block, constitutes not only a holder for the adjusting-nut, but also in connection with the head *b*⁴ of said nut a 25 handle by which the instrument may be conveniently manipulated.

In the operation of the instrument the legs *a a* may be brought to their approximate adjustment quickly by loosening the nut *f*³ and 30 moving said legs apart or together, as required, and then having tightened said set-screw the adjusting-nut *b*³ may be worked to bring the legs *a a* to an exact or minute adjustment.

35 The particular shape or office of the instrument-legs is immaterial to my invention.

I claim—

1. An instrument of the character described, comprising a pivot-block having a 40 socketed projection, a pair of legs jointed to said block, an adjusting-nut rotatable in the pivot-block, a rod extending through the pivot-block and adapted to slide therein, the upper portion of the rod having a screw-thread 45 connection with the adjusting-nut, a pair of links pivoted to the legs, a sleeve pivoted to

the links and having means for detachable connection with the rod, and a spring interposed between the socket and the adjusting-nut. 50

2. An instrument of the character described, comprising a pivot-block having a socketed projection, a pair of legs jointed to said block, an adjusting-nut rotatable in the pivot-block, a rod extending through the 55 pivot-block and adapted to slide therein, the upper portion of the rod having a screw-thread connection with the adjusting-nut, a pair of links pivoted to the legs, a sleeve pivoted to the links, a transverse threaded stud 60 movable in the sleeve and formed to bear on the rod within the sleeve, and a clamping-nut engaged with the stud and bearing against the sleeve.

3. An instrument of the character specified, comprising a pivot-block, a pair of legs jointed to the block, a rod movable in the pivot-block and projecting below the same, means carried by the pivot-block for adjusting the rod lengthwise, a pair of links pivoted to the legs, a sleeve pivoted to the links, a transverse stud movable in the sleeve and formed to bear on the rod within the sleeve, and a clamping-nut engaged with the stud and bearing against the sleeve. 70 75

4. An instrument of the character specified, comprising a pivot-block having trunnions, a pair of legs fitted to swing on said trunnions, means for retaining the legs on the trunnions, a rod movable in the pivot-block and projecting below the same, means carried by the pivot-block for adjusting the rod, a pair of links pivoted to the legs, and a sleeve pivoted to the links and provided with means for detachable connection with the 80 rod. 85

In testimony whereof I have affixed my signature in presence of two witnesses.

WILLIAM C. DAY.
